[57] CLAIM

The ornamental design for lighted headphones, as shown and described.

DESCRIPTION

FIG. 1 is a front and left side perspective view of a lighted headphone showing my new design; FIG. 2 is a left side elevational view thereof; FIG. 3 is a right side elevational view thereof; FIG. 4 is a top plan view thereof; FIG. 5 is a rear elevational view thereof; FIG. 6 is a bottom plan view thereof; FIG. 7 is a front elevational view thereof.

FIG. 8 is a front and left side perspective view of a second embodiment of the headphones illustrated in FIG. 1; and

FIG. 9 is a left side elevational view of the embodiment disclosed in FIG. 8.

The views of the second embodiment not illustrated are the same as the corresponding views of the first embodiment.

The cord is broken away in the drawing figures for ease of illustration.
